UNITED STATES PATENT OFFICE

WILLIAM H. CHAPMAN, OF MONTCLAIR, NEW JERSEY, ASSIGNOR TO GENERAL MOTORS CORPORATION, OF DETROIT, MICHIGAN, A CORPORATION OF DELAWARE

CENTERLESS GRINDER

Original application filed February 12, 1926, Serial No. 87,940. Divided and this application filed February 19, 1929. Serial No. 341,112.

This invention relates to centerless grinding and comprises all the novel subject matter herein disclosed. An object of the invention is to provide improved mechanism and steps for setting up centerless grinding machines preparatory to grinding a work-piece to a given size. Another object is to provide mechanism for definitely establishing an unvarying reference axis on the machine so as to locate the work guiding means and slow wheel in positions to fit the work at its desired finished diameter and to produce the same path of travel for work of any selected diameter.

To these ends and to improve generally upon machines of the character indicated, the invention also consists in the various matters hereinafter disclosed and claimed.

The invention, in its broader aspects, is not necessarily limited to the particular embodiment selected for illustration in the accompanying drawings in which:—

Figure 1 is a plan view with some parts in section, the work guides being removed and the set-up mechanism being in operative position.

Figure 2 is a front elevation with some parts broken away.

Figure 3 is a side elevation of the work guides and associated mechanism partly broken away and in section.

Figures 4 and 5 are detail sectional views of the work guides.

Figure 6 is an end view of the slow wheel head and its carriage.

Figure 7 is a front view of the slow wheel head.

Figures 8 and 9 are central sections, taken at right angles to one another, of the carriage for the slow wheel head.

Figures 10 and 11 are diagrammatic views indicating a work piece being guided up to the wheels and passing between them, and Figure 12 is a plan view.

The numeral 8 indicates a hollow base frame supporting a pan or casting 10 having ways or tracks 12 for a slidable carriage 14 which supports a head 16 for an abrading wheel 18. The wheel 18 is the fast wheel having its hub 20 secured in any suitable way, as

by the clamp plate 22, to the tapered end of a shaft 24 which rotates on a normally fixed axis in sets of angular contact ball bearings 26 and 28 in the head 16. One set 28 of bearings has its race rings clamped to the shaft 24 and in the head. The other set 26 has its outer race rings slideable in the head and pressed in one direction by springs 30 to prevent play and wear. The shaft 24 has a pulley 32 driven at high speed by a belt 34 which extends down through an opening in the pan 10 to driving mechanism in the base frame.

For generating a cylindrical face on the fast wheel, there is provided a truing tool which is movable parallel to the wheel axis opposite to the line of travel of a work piece. This comprises dovetail ways 36 for a carriage 38 slideable by means of a screw 40 and a hand wheel 42. On the carriage is adjustably secured a threaded shaft or pin 44 having a diamond 46 projecting through a slot in a wheel guard 48 to engage the wheel.

On the other side of the pan are ways 50 for a carriage 52 which adjustably supports a rockable or tiltable head 54 for a wheel 56. The wheel 56 is the slow or control wheel and it is considerably wider than the fast wheel and projects more towards the work receiving side of the machine so that the work will first engage the slow wheel against which it is held while passing to the fast wheel. Wheel 56 has a hub 58 clamped to a shaft 62 by a clamp plate 60, the hub being hollow to embrace a portion of the rockable head 54. Shaft 62 is rotatably supported in sets of angular contact ball bearings 64 and 66 in the rockable head, the outer race rings of the set 66 being constantly pressed in one direction to prevent play and wear by springs 68 interposed between a flange in the head and a ring 70 which abuts against one of the outer race rings.

For driving the wheel 56 in the same direction as the wheel 18 and at slower speed, a bevel gear 72 on the wheel shaft meshes with a bevel pinion 74 on a shaft 76 mounted near one end on ball and roller bearings in a sleeve 78 projecting from the rockable head and mounted near the other end on roller

bearings 80 in a lateral extension 82 on an arm 84 of the rockable head. A gear 86 on shaft 76 meshes with a gear 88 attached to a pulley 90 driven by a belt 92 and rotatably mounted on a stud shaft 94 fastened in the lateral extension 82. The head 54 is tiltably adjustable in curved ways around an axis passing through the center of the slow wheel and through the work contacting portion of the fast wheel to vary the speed of work feed. This axis is also in line with the axis of the driving pulley 90 so that the driving gearing will act equally well in whatever tilted position the slow wheel is placed. As shown in Figures 6 to 9 there are curved ways 96 on the under side of the rockable head engaging corresponding tracks or ways 98 in the supporting carriage 52, both sets of ways being curved about the described axis as a center. Adjustment of the head and bracing or support of the overhung parts is effected by a turnbuckle 100 having its right and left threaded portions pivotally connected to a plate 102 on the carriage 52 and to a plate 104 which is fastened to the end cap 106 carrying the ball bearings 66. The sides of the rockable head have lateral extensions 108 engaged by locking eccentrics 110 carried on hand operated shafts 112 journaled in lugs 114 on one end of the carriage 52 and in a single lug 116 near the other end of the carriage. The head can be tilted in either direction from the horizontal so as to be capable of feeding work through the machine in either direction but preferably the work enters at the end shown in Figure 2 and the near end of the slow wheel shaft is tilted upwardly.

When the slow wheel of a centerless grinder is tilted or skewed, proper feed and grinding of straight cylindrical work-pieces between the wheels parallel to the fast wheel axis requires that the wheel be slightly concave. To produce the proper shape of wheel initially is a matter of some difficulty and requires a considerable calculation. According to the present invention, the proper shape is produced by a truing tool which is mounted to slide across the slow wheel always in a line parallel to and on a level with the center of the work path or parallel to the opposing line contact of the fast wheel. No matter what tilted position the head assumes, the tool generates a curved surface producing a line contact for the work piece. As shown, the carriage 52 has a bracket 117 with ways 118 for a slidable carriage 120 movable by a screw 122 actuated by a hand wheel 124. In standards 126 in the carriage 120 is adjustably mounted a threaded shaft 128 having a knurled operating collar 130 and a clamping screw 132. At the end of the shaft 128 is a diamond 134 which is on a level with the axis about which the head tilts to project through a slot in a wheel guard 136 to en-

gage the wheel. The diamond is thus movable across the slow wheel on a line parallel to the center of the work path and at the same level. Being diametrically opposite the center of the work, the desired curved contour is imparted to the slow wheel such that the wheel presents line contact to a cylindrical work-piece fed parallel to the fast wheel axis at the same level.

For use in setting up the work engaging instrumentalities to produce a given diameter of work and for preserving an unvarying reference axis by which these instrumentalities can be so located that all sizes of work will travel the same path, the following mechanism is provided. Secured to the pan at front and rear are pairs of standards 140 between which a centering rod or arbor 142 can be temporarily supported on taper centers 144 mounted on arms 146 each of which is pivoted at 148 to a standard 140. The front taper center is adjustable by a hand screw to aid in placing the centering rod in the true reference axis of the machine on a level with the wheel centers. The ends of the arms 146 have hand screws 150 arranged to enter tapped openings in the standards to lock the arms in horizontal position when the centering mechanism is in use or to lock the arms in vertical position when the centering rod is removed. The tapped openings 152 for holding the arms in vertical position are on the same standards as the pivots 148 and the others are on the other standards on a level with the pivots. In use, a sleeve S of the same size as the finished work desired is sleeved on the centering rod 142 and then the wheels are individually fed into working relation to this reference work-piece which then lies between the wheels at their point of nearest approach. The work supports and guides which will now be described are also moved to work engaging and guiding position and then the centering rod and its reference work-piece are removed.

The standards have opposed ways 154 for upper and lower pairs of vertically slidable blocks 156 which are split at the ends so that they can be secured in adjusted position by clamping bolts 158. The lower blocks carry a lower bar or work guide 160 and the upper blocks carry an upper bar or work guide 162, both guides being movable in unison towards or from each other. To the lower bar are clamped front and rear pairs of guide plates or jaws 164 which are inclined to engage and guide the sides of work pieces as indicated in Figure 10. The vertical webs of the plates are slotted as at 166 to receive clamping bolts 168 by which the plates may be set to contact with work-pieces of different diameters, the work-pieces also resting on the guide bars so that a three point contact is provided. The pairs of plates or jaws 164 guide the work up to the wheels and away from the wheels.

Opposite the slow wheel, the lower guide bar has a recess 170 for a vertical blade 172 having its upper end bevelled as at 174 to project a little above the bar and above a hardened wear plate 176 which may be detachably secured to the bar. The blade has slots for clamping screws 178 and is vertically adjustable by screw bolts 180 threaded in the bar and abutting against the lower end of the blade. The upper bar has a recess 182 for an upper blade 184 which has its lower end bevelled, as at 186, to project below the upper bar and its wear plate 188. This blade is yieldable upwardly against the tension of a leaf spring 190 interposed between the upper edge of the blade and the top of the recess. Downward movement of the blade is limited by adjustable stop screws 192 threaded in the blade and passing loosely through openings in the bar. The blade is guided by a cover plate 194 abutting a ledge 195 in the recess and held against the ledge by bolts 196 having flats on their heads so that the blade can be removed on a partial turn of the bolts. The bevelled blades tend to hold the work pieces against the slow wheel so that rotation is imparted to the work before the work reaches the fast wheel and hence the likelihood of grinding a flat on the work or the likelihood of the end of the work piece hitting the side of the wheel is eliminated. The upper guide bar 162 normally has a very slight clearance with work-pieces but prevents them from rising or tilting.

The work guiding bars and their slide blocks are movable towards or from each other simultaneously by the following mechanism. The lower slide blocks 156 are carried by rotatable jack screws 198 guided loosely in the base of the standards and supported and fed endwise by worm wheels 200 which are connected for simultaneous rotation by a shaft 202. The upper slide blocks 156 are suspended by rotatable screws 204 guided loosely through cross bars 205 connecting the standards and supported and fed endwise by worm wheels 206 which are connected for simultaneous rotation by a shaft 208. The worm wheels 200 and 206 at the front are driven by worms 210 and 212 respectively and the worm shafts are connected by sprocket wheels 214 and a sprocket chain 216, the upper worm shaft being controlled by a hand wheel 218. The above described mechanism will cause the upper and lower guide bars to approach or recede from one another in equal degree so that work pieces of different diameters will be supported on a level with the wheels. Individual adjustment is however provided for by fixing to the jack screws hand wheels 219 which will enable either screw to be turned individually to feed it past its worm wheel.

The slow wheel is fed towards or from the work by a shaft 220 having a geared connection with the carriage 52 as indicated in part at 222. The shaft has an operating hand wheel 224 for quick rotation. A hand lever 226 is rockable between spaced limit stops 228 and carries a pawl 230 engaging ratchet teeth on the hand wheel to effect a slow feed. The fast wheel carriage 14 is fed in a similar way, the operating wheel being indicated at 232. The numeral 234 indicates a controlling wheel for a central prop or support (not shown) for preventing sag of the lower guide bar. The belt 34 of the fast wheel runs down around a drive pulley 236 in the base and is kept tight by an idler pulley 238 controlled by a weighted arm 240. The belt 92 of the slow wheel is led down around a drive pulley 242 and the drive pulleys receive power from any suitable power transmitting gearing preferably including change speed mechanism.

In setting up, the arms 146 are swung down to horizontal position and the rod 142, with a dummy or master work-piece sleeved upon it, is held by the taper centers in the true reference axis of the machine which is the line traversed by the centers of all work-pieces. This establishes the position the product piece will occupy at its finished diameter. The work guides and the slow wheel are then moved into contact with the piece. Upon removing the centering rod 142 and swinging up the arms 146, the machine is ready for grinding, the grinding wheel being fed in as required to remove the desired amount of stock. Preferably the work-pieces are fed in a stream by any suitable mechanism through the work guides until the wheels are reached. The slow wheel, being tilted, then controls the endwise feeding and rotation of the work. In any tilted position, the slow wheel can be dressed and the contour produced is such as to maintain a line contact with the work-pieces.

This application is a division of my co-pending application Serial Number 87,940.

I claim:

1. In a centerless grinding machine, a fast wheel, a slow wheel, a work support, a locating rod extending between the wheels, and means for temporarily supporting the rod in a definite and established axis of reference between the wheels; substantially as described.
2. In a centerless grinding machine, a fast wheel, a slow wheel, a work support, a locating rod extending between the wheels, and aligned centering members for temporarily supporting the rod in a definite and established axis of reference on the machine; substantially as described.
3. In a centerless grinding machine, a fast wheel, a slow wheel, a work support, a locating rod extending between the wheels, centering members for supporting the rod in a definite and established axis of reference on

the machine and means for moving one of the centering members; substantially as described.

4. In a centerless grinding machine, a fast wheel, a slow wheel, a work support, a locating rod extending between the wheels, taper centers for supporting the rod in a definite and established axis of reference on the machine, and supporting arms for swinging the taper centers into and out of operative position; substantially as described.

5. In a centerless grinding machine, a fast wheel, a slow wheel, a work support, a locating rod extending between the wheels, taper centers for supporting the rod in a definite and established axis of reference on the machine, supporting arms for swinging the taper centers into and out of operative position, and means for securing said arms in either position; substantially as described.

6. In a centerless grinding machine, a fast wheel, a slow wheel, a work support, a locating rod extending between the wheels, taper centers for supporting the rod in a definite and established axis of reference on the machine, supporting arms for swinging the taper centers into and out of operative position, and means for moving one of the taper centers in the direction of its axis; substantially as described.

7. In a centerless grinding machine, a fast wheel, a slow wheel, an upper work guide, a lower work guide, a locating rod extending between the wheels and between the work guides, and means for supporting the rod in a definite and established axis on the machine; substantially as described.

8. In a centerless grinding machine, a fast wheel, a slow wheel, work guiding means, a locating rod extending between the wheels, means for supporting the rod in a definite and established reference axis on the machine, and a reference or master work-piece sleeved on the rod; substantially as described.

9. In a centerless grinding machine, a fast wheel, a slow wheel, a work guide, means for supporting a reference or master work-piece on an axis extending between the wheels, and means for moving the work guide and slow wheel up to the supported piece to establish the finished size position of the corresponding product work-piece; substantially as described.

10. The method of setting up centerless grinding machines having a fast wheel, a slow wheel, and work supporting means which consists in supporting a reference or master work-piece in a definite and established axis extending between the wheels, moving the work supporting means and slow wheel up to the supported piece, and removing the piece; substantially as described.

11. In a centerless grinding machine, a frame, a grinding wheel rotatable at a grinding speed, a control wheel rotatable at a rela-

tively slower speed to control the rotation of work-pieces, means for definitely establishing an unvarying reference axis on the machine frame, and means for locating the axis of dummy workpieces of different diameters selectively in said axis of reference whereby the external surfaces of any of such selected pieces will locate said control wheel for external contact with product pieces of corresponding diameters when their axes are in said axis of reference; substantially as described.

12. In a centerless grinding machine, a frame, a grinding wheel rotatable at a grinding speed, a control wheel rotatable at a relatively slower speed to control the rotation of work-pieces, means for definitely establishing an unvarying reference axis on the machine frame work-guiding means between the wheels, and means for locating the work-guiding means with respect to said axis of reference to produce the same location for the axes of work-pieces of different diameters selectively; substantially as described.

13. In a centerless grinding machine, a frame, a grinding wheel rotatable at a grinding speed, a control wheel rotatable at a relatively slower speed to control the rotation of work-pieces, means for causing axial feed movement of the work-pieces between the wheels, means for definitely establishing an unvarying axis on the machine frame, work-guiding means between the wheels, and means for adjusting the work-guiding means and the control wheel with respect to said axis of reference to produce the same path of travel for axes of work-pieces of different diameters selectively; substantially as described.

14. In a centerless grinding machine, a frame, a grinding wheel rotatable at a grinding speed, a control wheel rotatable at a relatively slower speed to control the rotation of a work-piece, a work support, and centering means mounted on the frame for establishing the axis around which the work-piece is to be rotated during the grinding action; substantially as described.

15. In a centerless grinding machine, a frame, a grinding wheel rotatable at a grinding speed, a control wheel rotatable at a relatively slower speed to control the rotation of a work-piece, a work support, and taper centers aligned with one another to establish the axis of rotation of the work-piece; substantially as described.

16. In a centerless grinding machine, a frame, opposed grinding and control wheels forming a work receiving throat between them, a pair of centering members carried by the machine frame in alignment with the throat for establishing the axis around which a work-piece is to be ground, a work support carried by the frame and projecting between the wheels, and means for adjusting said support to peripherally engage and support

a work-piece for rotation on its established axis; substantially as described.

17. In a centerless grinding machine, a frame, a grinding wheel and a control wheel spaced to form a work-receiving throat between them, a pair of centering members aligned with the throat for establishing the axis around which a work-piece is to be ground, a work support carried by the machine frame and projecting between the wheels, and means for adjusting said support to peripherally engage and support a work-piece after its axis is established within the throat, one of said centering members being movable endwise towards or from the other; substantially as described.

18. In a centerless grinding machine, a frame, a grinding wheel and a control wheel spaced to form a work-receiving throat between them, a pair of centering members aligned with the throat for establishing the axis around which a work-piece is to be ground, a work support carried by the machine frame and projecting between the wheels, and means for adjusting said support to peripherally engage and support a work-piece after its axis is established within the throat, and at least one of the centering members being movable laterally with respect to said axis, to a position out of line with a located work-piece; substantially as described.

19. In a centerless grinding machine, a frame, a grinding wheel and a control wheel opposed to one another to form a grinding throat between them, centering members carried by the frame, the wheels being adjustable with respect to each other and to the centering members, a work support between the wheels, and means for adjusting the work support towards or from the grinding throat and transversely with respect to the direction of adjustment of the wheels; substantially as described.

20. In a centerless grinding machine, a frame, a grinding wheel and a control wheel opposed to one another to form a grinding throat between them, work centering members carried by the frame at the ends of the throat and establishing a line of reference, a work support projecting into the throat, and means for adjusting the work support and the wheels towards or from the line established by the centering members; substantially as described.

21. In a centerless grinding machine, a frame, a grinding wheel and a control wheel opposed to one another to form a grinding throat between them, a work support projecting into the throat, centering members at each end of the throat and in alignment therewith for establishing the axis of a work-piece to be ground, means for adjusting the distance between said members, and means for moving at least one of said members into

and out of alignment with the throat; substantially as described.

22. In a grinding machine, a frame, a grinding wheel, mechanism comprising a pair of centers for determining the axis of rotation of a work-piece to be ground, means peripherally supporting the work-piece for rotation while it is being ground, and a member frictionally engaging the work-piece for controlling the rotation thereof; substantially as described.

23. In a grinding machine, a frame, a grinding wheel, a work locating device carried by the frame for determining the axis of rotation of a work-piece to be ground, a work support peripherally supporting the work-piece while it is being ground, and a member frictionally engaging the work for controlling the rotation thereof; substantially as described.

In testimony whereof I hereunto affix my signature.

WILLIAM H. CHAPMAN.
